UNITED STATES PATENT OFFICE.

RUSSELL F. STEININGER, OF LEWISTOWN, PENNSYLVANIA.

PAPER-HANGING MACHINE.

1,199,313.

Specification of Letters Patent. Patented Sept. 26, 1916.

Application filed August 28, 1913. Serial No. 737,185.

To all whom it may concern:

Be it known that I, RUSSELL F. STEININGER, a citizen of the United States, residing at Lewistown, in the county of Mifflin and State of Pennsylvania, have invented certain new and useful Improvements in Paper-Hanging Machines, of which the following is a specification.

This invention relates to improvements in machines for hanging paper and one of the objects is to provide a machine which is capable of being manually supported and bodily moved along the surface to which paper is to be applied.

15 A further object of the invention is to provide means for applying paste to the paper as the same is advanced toward a wall or surface, and in this connection, a special novel feature consists in providing a convertible machine of this character whereby a single machine may be used for hanging paper on a vertical wall or on a horizontal ceiling.

20 A still further object of the invention is to provide paper guiding rolls which are so disposed as to permit of certain of the rolls being used when the machine is being utilized for papering a wall, and other of the rollers being used when the machine is utilized for papering the ceiling, the disposition being such that no adjustment of the rollers themselves will be necessary.

25 A further novel feature consists in an improved form or spring mounting for the machine whereby the latter when supported by the user will be held in an approximately operative position which it would assume if applied to the surface on which paper is being hung, the said means being convertible so that it will act with equal efficiency either when the machine is used for papering a vertical wall or a horizontal ceiling.

30 A further object of the invention is to provide an improved form of paper cutting means adapted to be readily operated to sever the paper at a point closely adjacent to the applying or hanging roller so as to enable the operator or user to make a fairly accurate sight calculation as to the proper length necessary in finishing an upward or final movement.

35 Other novel features of the invention will be more fully described in connection with the accompanying drawings, and will be

more particularly pointed out in and by the appended claims.

In the drawings:—Figure 1 is a view in side elevation of a paper hanging device embodying one form of my invention showing the same in full lines for vertical work, and in dotted lines for horizontal work. Fig. 2 is a rear view thereof. Fig. 3 is a sectional view on line 3—3 of Fig. 2. Fig. 4 is a sectional view on line 4—4 of Fig. 1. Fig. 5 is a side view of a portion of the machine showing the improved form of spring mounting.

40 Like characters of reference designate similar parts throughout the different figures of the drawings.

45 As shown, the device of my invention comprises frame side or supporting members 1 and 2 connected in suitable spaced relation by transverse rods 3.

50 Near one lower corner of the frame I have removably journaled a paper roll carrying spindle 4 having one end provided with a polygonal head 5 adapted for insertion in a similarly formed opening 6 in the frame side 1 so as to prevent rotation of said carrying spindle. It is the intention that the fixed spindle will be shaped to fit snugly in a core or longitudinal opening of the paper roll 7 so as to provide for considerable drag against unwinding rotation of the paper roll 7, and I also dispose the same on that part 55 of the machine which in any adjustment will be lowermost so that the paper will travel or be advanced upwardly from the roll. The paper from the roll 7 is trained about an idler guide roller 8, and the disposition of the roll 7 is such that 9 will be the wrong side and 10' the right side of the paper. The paper is continued over a guide roller 10 and rearwardly therefrom over guide roller 12. 60 From guide roller 12 the paper is guided over a roller 13 to a hanging or applying roller 14 which latter functions to apply or hang the paper to the wall or ceiling surface. Rearwardly of roller 14, with respect to the direction of operation of the machine, I provide a smoothing or finishing roller 15, the function of which is to follow the applying roller and smooth out any lumps of 65 paste that may cause the paper to project and also force out confined air so as to render the device as efficient as possible for smoothly hanging the paper. The roller 8

is mounted upon a spindle 16, journaled in the frame sides, in any suitable manner, and rollers 10, 12, 13, 14 and 15 are also provided with spindles 17, 18, 19, 20 and 21, respectively, all of the rollers being preferably freely mounted on their spindles, except roller 14.

During passage of the paper prior to its engagement with the applying roller 14, I 10 apply paste to the wrong side 9 thereof, and the paste applying means may be of the following construction:—A paste box 11 which may be of an approximately trough or U-shaped cross section is pendants journaled on a spindle 22 which is mounted in the frame sides. The spindle 22 serves as a mounting for a brush consisting of a core 23 and radially disposed bristles 24 mounted thereon. As will be seen by reference to 15 Fig. 3, the brush is in a position to apply paste to the wrong side 9 of the paper during the lap or run from roller 10 to roller 12 when the machine is used for vertical work. It will also be seen that the disposition 20 of the parts is such as to flex those bristles engaging the paper so as to provide for a more effective application of the paste. I 25 preferably drive the brush from the paper applying or paper hanging roller 14 and 30 therefore the latter may be rigidly mounted on its spindle 20 and the latter may be provided with a sprocket wheel 25 disposed on the outside of the frame member 1. The spindle 22 carries a sprocket wheel 26 over 35 which and the sprocket 25 a sprocket chain 27 may be trained. Upward movement of the machine will impart rotation to the paper hanging roller 14 in the direction of the arrow shown in Fig. 1, and therefore the 40 brush 24 will be rotated in a direction reverse to the advancing movement of the paper to which the brush will apply paste, this arrangement being the most efficient means of obtaining an efficient application 45 of the paste.

In order to prevent movement of the paste receptacle, means is provided which may consist of a set screw 28 which has threaded engagement with the frame side 1, and extends into engagement with the receptacle 50 11. I may also provide the receptacle 11 with filling opening adapted to be closed by a cap 29.

At a point preferably closely adjacent the 55 applying roller 14, I provide means for severing the paper.

As illustrated, the frame sides 1 and 2 are slotted as indicated at 30 and 31, respectively, and a paper knife preferably in the 60 form of a blade 32 is disposed in said slots with its knife edge projecting toward the paper, as is clearly shown in Fig. 3. One end of the knife will be pivoted in the side frame 2, as indicated at 33. The other end 65 of the knife will be connected with operat-

ing means which may be in the form of a cord 34 adapted to be guided through an opening in a guide plate 35 and over a guide roller 38 downwardly along the machine through an eye 37. The cord is guided in such a manner that a pull on the same will lift the knife at one end so that a shear cut or severance of the paper will be effected. If desired, any form of opposing strip 2' may be provided above the knife blade to prevent 70 elevation of the paper under the lifting and cutting action of the knife. The knife will in most instances descend by gravity from a cutting position but in order to insure its return to the position shown in Fig. 1, I 75 may provide a spring 38 having one end secured to the knife and the other end to the frame side 1.

The hereinbefore described machine is adapted for manual manipulation and operation by means of a handle 39 which may be provided with arms 40 and 41, having cranked ends 42 and 43, respectively, journaled in the frame side, as shown. The handle 39 may be provided with one or more 80 guides 44 for retaining the knife-operating cord 34 in convenient proximity to the operator.

It will be noted that the connection of the handle with the machine or frame thereof 85 is at a point laterally of the center of gravity thereof, and for the purpose of maintaining the machine in a general position adapted for engagement with a wall, I provide spring positioning means which I will 90 now describe in detail.

On the cranked end 43 I provide an arm 45 adapted to be adjustably held in any desired position by a set screw 46. At the upper end of the arm 45 a tension spring 47 105 is connected, the other end of the tension spring 47 being connected at 48 to the side wall 2. A tension spring 49 is also connected at one of its ends with the lower end of the arm 45, its other end being connected 110 at 50 to the side wall 2. It will be readily seen by reference to Fig. 5 that tilting movement of the handle 39 at different inclinations will impart different tensions to the springs, and the latter will respond by rocking the machine proper on the handle to the desired inclination or position and the opposing springs will resist movement of the machine from the position in which it is being supported. Should it be desirable to 115 place spring 47 under a greater tension than spring 49, suitable adjustment of the arm 45 may be made for this purpose. Owing to the fact that a machine will have a much greater use for hanging paper on vertical 120 walls, it may be desirable and I preferably provide the upper spring 47 of greater strength than the lower spring 49. I will now describe the manner in which the device of my invention is used.

The supporting spindle 4 will be withdrawn and a roll of paper will be inserted between the frame sides and supported upon reinsertion of the spindle 4. The paper will then be advanced by and over rollers 8, 10, 12, 13 and 14, successively, and a slight manual rotation of the brush may be effected at the start in order to coat with paste the starting length of the paper after which this will be unnecessary. The machine will be so positioned as to engage the roller 14 with the wall surface 51 and the machine will be advanced upwardly along the wall surface. The operator will apply power to the handle to engage the roller 14 with the wall surface with a relatively considerable pressure, such pressure being substantially equalized between the hanging roller 14 and the smoothing or finishing roller 15. When the machine reaches a point approximately near the top of the wall, the user will gage the remaining distance not papered and at the proper time he will pull the cord 34 and operate the knife to sever the paper, whereby the upward movement of the machine will be continued to finish the hanging of one strip. In succeeding operations, it will merely be necessary to advance the severed end over the roller 14 in order to start a new strip. I will next describe how the machine is converted for papering ceilings without necessitating any roller adjustment.

In Fig. 1, I have shown in dotted lines a horizontal adjustment of the machine and when this horizontal adjustment is made a corresponding adjustment of the arm 45 will likewise be effected. In the horizontal position, the set screw 28 will be released so as to permit the paste receptacle to swing so that it will open upwardly from a position at right angles from the open top as disclosed in Fig. 3, so as to prevent the paste from being spilled. The set screw 28 will then be turned to anchor the receptacle. In this horizontal working position, the paper will be extended directly from roller 8 to roller 13, as shown in dotted lines in Fig. 3, so as to bring the paper abreast of the paste applying brush 24. The position of the spindle 22 and the position of spindles 16 and 19 will be such that when the paper is trained over said rollers in the manner indicated, contact of the brush will be effected without necessitating any adjustment of the roller.

The hanging and finishing rollers 14 and 15 will operate in the same manner as in the vertical working position, and the machine will otherwise operate the same.

It is believed that the advantages and utilities of the invention will be fully understood from the foregoing description, and while I have herein shown and described one specific form of the invention, I do not wish

to be limited thereto, except for such limitations as the claims may import.

I claim:

1. A paper hanging machine comprising in combination, mechanism for applying paper to a wall surface, a supporting and operating handle connected with said mechanism at a point laterally of its center of gravity, and spring means connecting said handle with said mechanism whereby the position of said mechanism may be regulated in accordance with the position in which said handle is held, substantially as described. 70

2. A paper hanging machine comprising in combination, mechanism for applying paper to a wall surface, a supporting and operating handle pivotally connected to said mechanism, an arm adjustably connected with said handle at the point of pivotal connection thereof with said mechanism, and operating springs connected with said arm and with said mechanism, substantially as described. 80

3. A paper hanging machine comprising in combination, a frame provided with a plurality of paper guiding rollers for guiding the paper in prescribed paths of movement through said frame, a paste applying means for applying paste to the paper during its movement through said frame, and mounted for adjustment about a fixed axis, means for supporting said frame in horizontal or vertical working positions, a device for adjusting the paste applying means for vertical or horizontal working positions, said guide rollers being disposed with respect to the paste applying means so as to permit of the paper being trained over certain of said rollers for engagement with said paste applying means for one working position and over other rollers for engagement with said paste applying means for another working position and means on said frame for applying paper to a wall surface, substantially as described. 90

4. A paper hanging machine comprising in combination, mechanism for applying paper to a wall surface, a supporting and operating handle connected with said mechanism, spring means connecting said handle with said mechanism whereby the position of said mechanism may be regulated in accordance with the position in which said handle is held, and means for regulating the tension of said spring means as and for the purpose set forth. 105

5. A paper hanging machine comprising in combination, mechanism for applying paper to a wall surface, a supporting and operating handle pivotally connected with said mechanism at a point laterally of its center of gravity, an arm rigidly secured to said handle adjacent its pivotal connection with said mechanism, springs attached to 125

the ends of said arm and in connection with said mechanism whereby the position of said mechanism is regulated in accordance with the position in which said handle is held substantially as described.

6. A paper hanging machine comprising in combination, mechanism for applying paper to a wall surface, a supporting and operating means connected with said mechanism and a second means in connection with said operating and supporting

means and said mechanism whereby the position of said mechanism may be regulated in accordance with the position in which said supporting and operating means is held, 15 substantially as described.

In testimony whereof I affix my signature in presence of two witnesses.

RUSSELL F. STEININGER.
